UNITED STATES PATENT OFFICE.

THOMAS W. LEONARD, OF RICHMOND, VIRGINIA.

NON-REFILLABLE BOTTLE.

No. 926,580.

Specification of Letters Patent. Patented June 29, 1909.

Application filed June 8, 1908. Serial No. 437,351.

To all whom it may concern:

Be it known that I, THOMAS W. LEONARD, a citizen of the United States, and a resident of Richmond, in the county of Henrico and 5 State of Virginia, have made certain new and useful Improvements in Non-Refillable Bottles, of which the following is a specification.

This invention is an improvement in non-10 refillable bottles and has for an object to provide a novel construction in which the ordinary external appearance of the bottle will be preserved, the bottle neck will be strengthened where desired, the bottle can be easily 15 filled and sealed, and in which the dispensing of the contents of the bottle can be readily accomplished, the sealing devices being adapted to move from sealing to unsealed position for such purpose, as will more fully 20 appear hereinafter; and the invention consists in certain novel constructions and combinations of parts as will be hereinafter described and claimed.

In the drawing—Figure 1 is a vertical 25 longitudinal section of a bottle embodying my invention. Fig. 2 is a cross section thereof on about line 2—2 of Fig. 1. Fig. 3 is a cross section on about line 3—3 of Fig. 1. Fig. 4 is an inverted view illustrating the 30 position of parts for dispensing the liquid from the bottle, and Fig. 5 shows a somewhat different form of check valve.

The bottle has the body A, which may be of any suitable form and the neck B, which is 35 contracted at B' to form a seat for the check valve A', which check valve may be globular as shown in Fig. 1, or may, if desired, be of the pear-shape shown in Fig. 5 or of other suitable form. The neck is thickened and 40 thus reinforced from its mouth C downward and this reinforcement is provided on the inner side of the neck, thus furnishing the desired strength and affording the shoulder

C' at the lower end of the thickened portion 45 without affecting the external appearance of the neck and at the same time this forms the broad shoulder C' at the inner end of the thickened portion of the neck and a broad seat at the lip C for the packing ring D, 50 see Fig. 1. Grooves E are formed longitudinally in the inner face of the thickened portion of the neck and afford passages for the discharge of the liquid when the bottle is adjusted to the position shown in 55 Fig. 4 and in the lower or inner end of the thickened portion I provide in the shoulder

C' notches C², preferably arranged diametrically opposite each other and adapted to receive the ends of a spring bar F, which constitutes the means for retaining the stopper G 60 when the latter is adjusted into the neck of the bottle. This stopper G is fitted to the neck of the bottle, is provided at its outer end with a head G', which overlies the lip C of the bottle neck, and the stopper is of such length 65 as to extend, when in the position shown in Fig. 1, down to and bear at its inner end against the valve A' and hold the said valve to its seat when the parts are in the position shown in Fig. 1. The packing D fits beneath 70 the head G' of the stopper G and is pressed thereby tightly against the lip of the bottle neck.

The spring bar F extends through a transverse opening G² in the lower portion of the stopper G and the bar F has its ends F' upturned to bear beneath the shoulder at the lower end of the thickened portion of the bottle neck and preferably within the notches C² formed in the said shoulder so that when the 75 parts are in the position shown in Fig. 1, the spring bar F will serve the double purpose of preventing the withdrawal of the stopper G, and in connection with the notches C² will 80 prevent any rotary movement or turning of 85 the stopper. In the position shown in Fig. 1 it may be preferred to form the bar F in such manner that its ends will not quite touch the base of the notches C² in order to give a greater movement to the stopper G in adjust- 90 ing the said stopper to position to permit the dispensing of the contents of the bottle. In this position it will be noticed the ends of the spring bar F will bear outwardly against the inner walls of the bottle neck and prevent 95 any accidental movement of the stopper to its outermost position, in which it would permit the pouring off of the contents of the bottle.

In operation the stopper and ball A' being 100 removed from the neck, the bottle may be filled in any desired manner, the valve A' applied, the packing D placed on the lip C and the stopper G pressed into the bottle neck, the ends of the spring bar springing up 105 against the stopper until the latter has been inserted to the position shown in Fig. 1, when the ends of the bar F will spring outwardly below the shoulder C' and the stopper may be turned to adjust it to position in which the 110 ends of the bar F will spring into the notches C². The bottle will then be securely closed

and the contents thereof be retained until such time as it is desired to dispense them, when the packing D may be cut away with a knife or other implement and the stopper be 5 pulled out slightly to release the ball A', when by inverting the bottle to the position shown in Fig. 4, its contents may be dispensed, flowing out through the open valve seat B', thence out of the groove or grooves 10 E in the inner face of the bottle neck as will be understood from the foregoing description.

The stopper and the ball are of glass and the spring bar of metal or other suitable elastic material.

15 It will be noticed that the bottle neck is reinforced by its thickened portion from the outer end or lip of the neck to the inwardly facing shoulder with which the locking bar engages.

20 I claim—

A bottle having its neck thickened on its inner side from its lip downwardly forming a broad lip at the outer end of the neck, and a shoulder at the inner end of the thickened

portion and having in said shoulder notches, 25 and provided in the inner face of the thickened portion with longitudinal grooves forming a passage for the liquid, the neck having below said shoulder a contracted portion forming a valve seat, a valve fitted to said seat, and a stopper of lesser diameter than the internal diameter of the neck and having at its outer end a head overlying the lip of the bottle neck and its body portion fitting in the bottle neck and extending at its inner end 30 to a position to bear upon the valve, and provided below the shoulder in the neck with a transverse opening, a spring bar passed through said opening and extending at its ends beyond the stopper and having said 40 ends upturned to bear within the notches in the shoulder of the bottle, and a packing between the lip of the bottle neck and the head of the stopper, substantially as set forth.

THOMAS W. LEONARD.
